SMOKER'S PIPE

Joseph F. Daly, Thomas J. Daly, and Carroll H.
Daly, Philadelphia, Pa.

Application December 31, 1936, Serial No. 118,498

2 Claims. (Cl. 131—12)

Our invention relates to a pipe for smokers' use and may be said in general to refer to tobacco pipes and cigar and cigarette tubes or holders.

The invention relates more particularly to a pipe having means for cooling the smoke passing therethrough so as to render the same most pleasing to the taste and prevent burning of the tongue and mouth, as well as to provide an improved construction of the same which will furnish a better taste when smoked, will draw more easily and will be more hygienic than pipes commonly in use for its parts may be easily disassembled for cleaning and other purposes.

In the construction of the pipe there is means for providing a sinuous or circuitous path for the smoke of some considerable length, together with means for enabling a very complete radiation of the heat so that the smoke is cooled effectually before reaching the mouth-piece at the end of the stem.

Among the many objects of the invention which may be mentioned may be named the production of a device of the kind described which is simple, compact, convenient, durable, satisfactory, reliable and efficient for use wherever it is found applicable and suitable.

With this and many other objects in view, the advantages and benefits of the construction herein shown and described will be obvious to those skilled in the art from the disclosure hereinafter made of the essential features and the details of the invention; and to this end, therefore, the invention may be said to consist in the novel construction, arrangement and combination of parts and in numerous details and peculiarities thereof as herein shown and described and then more conveniently pointed out in the claims.

In the accompanying drawing illustrating our invention, wherein like reference characters indicate like or corresponding parts,

Fig. 1 is a longitudinal sectional view of our improved pipe.

Fig. 2 is an outside elevational view of the same.

Fig. 3 is an enlarged partial sectional view of the stem and the foraminous or sieve-like members combined therewith and composing a part thereof to permit effectual heat radiation from the smoke as it passes through said stem.

Fig. 4 is a transverse section of the same on the line 4—4 of Fig. 3.

Fig. 5 is an enlarged sectional detail view of a portion of the inner end of the mouth-piece and the elongated rod provided with a series of baffle devices and inserted through the stem.

Fig. 6 is a sectional detail on the lines 6—6

of Fig. 5 and shows the faces of a pair of contiguous baffle plates.

Fig. 7 is a cross section on the line 7—7 of Fig. 5 and indicates the air passage for the smoke after it leaves the baffles and enters the mouth-piece.

Similar characters of reference designate corresponding parts throughout all the different figures of the drawing.

In the drawing wherein we have illustrated a preferred embodiment of the invention, there is shown a pipe having a bowl 1, of any usual form, the same being susceptible of a wide variation in size and shape, ornamentation and other characteristics. At the bottom of the bowl is an outlet passage 13 for the smoke, the same being usually substantially at the extreme bottom so that the smoke may have exit from the complete combustible area of the contents.

2 designates a mouth-piece of any qualified design or shape having therein a central passage 3, through which the smoke flows to the mouth and in which because of the peculiar construction of the stem and its several advantageous characteristics the smoke will be found to be considerably and markedly cooled by the time it reaches the mouth, the radiation being effectual.

The mechanism of the pipe which may be treated as the equivalent of what is ordinarily known as a pipe stem, that is to say, the member between the bowl and the mouth-piece, is constructed of several features which by reason of their combination and co-operative relation produce the results which demonstrate the value of our improved pipe.

The description of these parts of the stem is as follows:

The metallic tube of any preferred material, but usually some thin, but stiff metal, 4, is inserted and held tightly in the lower portion of the bowl 1, but is usually withdrawable for purposes of cleaning or adjusting. This thin tube enters the lower portion of the bowl far enough to provide a strong holding connection, and it is long enough to reach to the mouth-piece at a suitable distance therefrom so that the length of the stem and the mouth-piece together may be a reasonable one for the length of the pipe, but may be obviously variable and prepared in different sizes for different grades and sizes of manufacture.

At a suitable point on the tube 4 where it abuts against the bowl, in order to form a close joint thereagainst, is an integral collar 5, and at the end of the tube 4, the most remote from the bowl 1, is a similar integral collar 6. Between these

two collars 5 and 6, and closely surrounding the thin metallic tube or pipe 4, is wound a member of finely meshed fabric 11, which is folded back and forth upon itself in a manner similar to a bellows construction so that within the pouches of the mesh at 14, are open spaces of considerable size which obviously alternate with each other so that every other one is open against the tube 4, and every other one alternating therewith 10 is open against the wall of an outside meshed fabric 10 surrounding the element 11 in a close and tight manner, said cylindrical sieve-like element 10 being firmly secured at its ends to the disks or collars 5 and 6, as clearly portrayed in 15 Fig. 3.

The specific and exact form of the bellows-like member 11 may vary within wide limits and the alternate pouches 14, some of which members are open directly to the tube 4, while the rest 20 of the members are open directly to the external sieve cylinder 10, may be smaller or larger and rectangular or other angular as preferred, or curved if desired, in order to form recesses, the object being to provide these alternative bends in 25 the bellows material to enable the heat from the smoke to be radiated therethrough easily and promptly, and enabled to pass through the tube 4 to the sieve 10 and thus be carried into the atmosphere. The bends of the member 11 may 30 be in the form of flutes or corrugations to increase the surface. In other words, it may be said that the mesh or perforated material 11 is convoluted and provides a convoluted mesh-like envelope for the inner tube which is located between said tube forming the inner part of the 35 stem and the outer cylindrical mesh or foraminous member 10.

The size of the mesh of both members 10 and 11 may vary within wide limits. The character 40 of the material may be changed as preferred. In some instances a textile may be used in one or both cases, but usually it will be a metallic fabric. The object of course is to provide efficient means for withdrawing the heat from the smoke 45 and residue of combustion, and this is accomplished in a most desirable and satisfactory way by these foraminous elements.

It will be observed therefore, that alternate portions of the device 11 come into immediate 50 contact with the tube 4 and the outer sieve 10, whereby the surface for heat conduction is greatly increased.

The passage 13 which leaves the bottom of the bowl 1 delivers directly into the end of the tube 55 4 which is inserted into the adjacent part of said bowl.

The mouth-piece 2 against which the collar 6 abuts when the parts are assembled in service 60 position, carries an integral sleeve 7 of smaller dimensions, which enters the adjacent end of the tube 4, and therewith forms a suitable joint so that collar 6 which directly surrounds the sleeve 7 may be in close conjunction with the end of the member 2, and through this sleeve 7 runs 65 a passage 12 through which the smoke from the interior tube 4 reaches the delivery passage 3 in the mouth-piece 2.

There may obviously be any number of these 70 passages 12, (see Figures 5 and 7). Within the sleeve 7 is firmly secured the end of a rod or stem 8, which is adapted to be inserted into the tube 4 and has a length sufficient to enable it to reach entirely through or nearly so if desired, the said tube 4, although obviously the stem or rod 8 75 may have any desired length. It is equipped

with a series of alternating cam-shaped baffle devices preferably composed of curved or semi-circular tabs or plates 9 which are shown in side view in Fig. 6, two of these baffle plates being there indicated. They are completely semi-circular in shape, or a little more than a complete semi-circle, one portion of the plate being a complete semi-circle and the other portion on the other side of its axis having a slightly curved diametrical line, which is tangent to the 10 surface of the rod, the semi-circular portion of the baffles being in contact with the inner tube, and these baffle plates alternately project in opposite directions so their peripheries come into contact closely with opposite interior arcs of the 15 tube, 4. These baffle devices fill the interior space of the tube 4, and cause the smoke to follow a tortuous passage, delays its transit and gives more time to dissipate the heat in the smoke by radiation through the wall of the tube 20 4 and the surrounding foraminous elements.

We reserve the liberty of varying the exact form of the obstacles 9, in order to accomplish the best results, but it will be understood that they serve as obstructions for the passage of the 25 smoke and baffle it in its movement.

When the rod 8 carrying the projections 9 thereon is inserted into the tube 4, and the latter has been connected with the bowl, it will be evident that parts of the pipe are completely assembled for use for the entrance of the rod 8 which is carried by the mouth-piece 2, supports the latter on the tube 4, which is itself supported in the bowl, and when the parts are thus put together, the external cylindrical sieve 10 is flush with the end of the mouth-piece at one end and with the bowl at the other end so that it forms a single connection between the mouth-piece and the bowl, and through it the smoke loses a good portion of its heat.

In operation therefore, the pipe is assembled in this manner as shown in Figs. 1 and 2, after which tobacco can be placed within the bowl and ignited and burned in the usual manner.

As the smoker uses the pipe and applies suction at the mouth-piece the smoke ensuing upon combustion of the contents of the bowl is drawn through the stem toward the mouth, but the flow of the smoke is interrupted by the baffles so that the column of smoke moves slowly, giving it time to radiate its heat through the mechanism provided for that purpose which of course performs a filtration act upon the tobacco residue.

The sieve-like casing and the bent inner gauze, 55 or mesh receive and quickly deliver the heat units and radiate them outwardly into the atmosphere.

It has been found by practical demonstration that the cooling effect upon the smoke is most marked so that the result of the combination of parts in their effective operation is of great use and value. If the smoke which enters the mouth of the smoker has been previously cooled to a large extent, as is possible with our improved pipe, there is far less tendency to quicken the flow of saliva from the salivary glands and therefore obnoxious expectoration is eliminated. Further there is an absence of the usual objectionable collections in the bottom of the bowl and other 70 advantages too numerous to mention are the result of the use of the various parts related together as we have explained.

It will be further understood that the principal features of our invention which have been 75

set forth herein, may be readily applied to many and various forms of smoking pipes wherein by some slight change in design and without departing from the essential features of the invention, the same desirable results can be attained.

With respect to the form and material of the mesh sieve or strainers 10 and 11, it will be understood that the fineness or coarseness may vary as also the shape and size, and in respect of the member 11 its undulations or convolutions whether on the convex or concave side may vary greatly in all respects, particularly with regard to the bends and pouches alternating as shown, or in any other way. Therefore when a large volume of cool outside air passes through the interstices of the mesh and cools the smoke flowing through the inner tube of the pipe, these various cooling members will furnish large radiating surfaces for the heat contained in said smoke, thereby cooling the latter very effectually and enabling the smoke when it arrives at the mouth to have a very alluring taste and character.

What we claim is:

1. In a pipe having a bowl, a mouthpiece, and a stem connecting the bowl and mouthpiece, a passage through the bowl, stem, and mouthpiece, a tube positioned within the stem passage, a central rod of less cross-sectional dimension than the

cross-sectional dimension of the stem passage and baffle members in staggered relation secured to the rod, each baffle extending from one wall surface of the passage to the opposite side of the rod whereby an open tortuous passage is 5 provided within the stem passage.

2. The combination with a pipe having a bowl and a mouthpiece, a stem having a central tube, collars adjacent the ends of the tube, a member of finely meshed fabric surrounding the tube, 10 a cylindrical perforated element surrounding the mesh fabric and secured at its ends to the collars, said mesh fabric consisting of a cylindrical member having a plurality of folds intermediate the ends thereof and engaging the tube, the cy- 15 lindrical element, and the collars, and a baffle member positioned within the tube, said baffle member having a central rod of smaller diameter than the tube and substantially cam-shaped baffles at spaced intervals on the rod, each baffle 20 having an edge thereof of semi-circular form and an adjacent edge tangent to the surface of the rod, the semi-circular portion thereof being in contact with the inner tube whereby a tortuous smoke passage is provided in the stem. 25
